UNITED STATES PATENT OFFICE.

CORNELIUS S. CLARK, OF NORFOLK, VIRGINIA.

INDICATOR.

SPECIFICATION forming part of Letters Patent No. 784,472, dated March 7, 1905.

Application filed January 9, 1905. Serial No. 240,284.

To all whom it may concern:

Be it known that I, CORNELIUS S. CLARK, a citizen of the United States, residing at Norfolk, in the county of Norfolk and State of Virginia, have invented new and useful Improvements in Indicators, of which the following is a specification.

This invention relates to what I shall for convenience term an "indicator," it having as a part thereof a phonograph. I desire to state at this time that I use the term "phonograph" in its broad sense to include equivalent apparatus of other names. The device, as will be gathered from its title, involves indicating mechanism; and it is the primary object of the invention in a ready and simple manner to cause the operation of the indicating mechanism and the phonograph in unison. The indicating mechanism may be of any desirable character, it consisting in the present instance of recording means whereby a permanent record of an operation may be secured, and, as will be understood, simultaneously with the taking of the record the phonograph will be operated to announce the operation of the indicating or recording mechanism.

The device may be employed for various purposes—for example, in lieu of an ordinary cash-register—the parts being so organized that when a sale is made a permanent record of the amount of the sale will be secured and at the same time such amount will be announced by the phonograph.

In the drawings accompanying and forming a part of this specification I illustrate a simple organization of parts involving my invention; but I do not restrict myself to the showing thus made, for certain variations may be adopted within the scope of my claims.

In said drawings, Figure 1 is a vertical sectional elevation of an indicator including said invention. Fig. 2 is a sectional front view of said indicator. Fig. 3 is a horizontal sectional top plan view of the same. Fig. 4 is a detail in front elevation, showing the lever illustrated in the preceding views in cross-section. Fig. 5 is a detail of a printing member and a character formed by the same and

a coöperating printing member hereinafter more particularly described.

Like characters refer to like parts throughout all the views.

The different parts of the indicator may be housed within a case, denoted in a general way by 2 and which is substantially of the form like that familiar in existing types of cash-registers, the case being divided into upper and lower compartments by the horizontally-disposed wall 3. In the lower compartment of the case is situated the drawer or till 4, adapted as a receptacle for money and which is adapted to be locked in some positive manner in a retracted position within the case. To lock the drawer or till in its retracted position, I have represented a latch 5, pivoted between its ends upon a bracket or other support, as 6, secured to the rear wall of the case 2, in the lower compartment thereof. The latch is shown as held in its operative position by means of a spring, as 7, of coiled form, seated in a bore in the bracket 6 and exerting its power against what might be considered the tail or outer branch of the latch-lever 5. The case of course has an opening in its forward side to receive the front of the drawer or till and through which the drawer can be forcibly projected by some suitable means, as the coiled spring 8, bearing at its opposite ends against the rear of the drawer and the back wall of the case, interiorly of the latter. Said drawer and wall are represented as provided with projections or studs encircled by the terminals of the spring, which when the drawer is locked or held back by the latch 5 will be compressed, as indicated clearly in Fig. 1. When the latch 5 is tripped by pressure upon the tail thereof or in some other suitable way, the shouldered or working end thereof will be lifted above the rear wall of the drawer or till to effect the release of the latter, following which the said drawer will be shot forward by the power of the spring 8 in order to obtain access to the drawer to put money thereinto or remove same therefrom, as occasion may require.

The indicating mechanism is represented as consisting in the present instance of print-

ing devices adapted to act upon a ribbon or strip of paper, whereby a permanent record may be had of the operation of the machine. The printing devices may be of any desirable number, and in the present case they are situated within the upper compartment of the casing 2. The drawer or till 4 is guided between the vertical walls 9, extending from the bottom of the case 2 to the wall 3 and separated from the sides of the case in order to provide compartments, as 10, at opposite sides of the drawer, as indicated clearly in Fig. 2. In one of these compartments and supported by a suitable hanger or other device is situated a spool or reel, as 11, which carries the paper or ribbon upon which the imprint of cash sales is to be made, the ribbon or strip of paper or something of a similar character being unwound from the spool 11 or reel and passing into the compartment 10 on the left in said Fig. 2, the spool or reel being, as will be understood, situated in the other compartment. In its course the ribbon or paper passes between the coöperating feed-rolls 12, arranged in superposed order above and at one side of the compartment 10 on the left, into which compartment the leading or free end of the ribbon is received. The lower roll 12 is fixedly connected with the shaft 13, extending in a direction from the front to the rear of the machine and supported by a suitable bearing mounted upon the upper side of the wall 3. To insure the proper feed of the paper strip or ribbon, I may circumferentially roughen the lower roll 12. Horizontally alined with said lower roll 12 is a guide-roll 14, supported in some suitable manner just above the compartment 10 on the right in Fig. 2.

Connected with the case 2, in the upper compartment thereof, is a box-like part 15 open at its opposite ends, as indicated clearly in Fig. 2, for the passage of the paper, tape, or ribbon unwound from the reel or spool 11, said paper between the roll 14 and the lower roll 12 traversing the upper side of the table 16, illustrated as a plate mounted within the box-like part 15 and horizontally disposed.

Above the top of the box-like part or housing 15 in the upper compartment of the casing is a flange 17, horizontally disposed and having downwardly-disposed webs at its ends united with the top of the box-like part or housing 15. The flange 17 is perforated to receive the enlarged heads of vertically-disposed printing members, (each designated by 18,) the shanks of said printing members being surrounded by coiled springs 19, bearing against the top of the housing or box-like part 15 and against shoulders located below the heads of the respective printing members to hold the latter normally in an elevated position. The printing members, as will be seen upon an inspection of Fig. 3, are obliquely arranged with respect to the front of

the casing 2. Each printing member 18 carries at its lower end an impression device, the upper side of the table or plate 16, which is traversed by the paper or the ribbon from the spool or reel 11, having similar impression devices, denoted each by 20. (See Fig. 1, for example.) The printing members 18 will carry male impression devices, while the female impression devices will be supported by the table 16. The shanks of the printing members 18 pass through perforations in the top of the housing or box-like part 15. When one of them is depressed, the impression device at the lower end thereof will move toward a vertically-alined and coöperating impression device, the two coöperating to cut through the paper the character which they bear, which character may be of any suitable kind, such as a numeral or series of numerals, as will be understood from an inspection of Fig. 5, and each time the apparatus is operated the depression of a printing member will occur, so that a record will be secured of such operation.

The phonograph for announcing the operation of the indicating mechanism, consisting, as will be understood, in the present case of the printing devices, is denoted in a general way by 21 and is illustrated as supported in the upper compartment of the case 2. It will be understood from what I have hereinbefore stated that I use the term "phonograph" to include within its meaning other sound-reproducing devices than "phonographs," so called. The phonograph includes in its make-up a record 22, which is illustrated as being of cylindrical form, but which may be of any other suitable character. The record-cylinder is removably mounted upon a mandrel, as 23, having a circular head 24, the function of which will be hereinafter described. The phonograph 21 may be operated in any desirable way—for example, by a motor, which may be a spring-motor, which I deem it unnecessary to illustrate. The motor will be connected with the phonograph in any desirable way—for example, by means of gearing connected with the gear 25 on one end of the shaft of the mandrel 23, as indicated clearly in Fig. 3.

In connection with the phonograph I provide a feed-controlling device which, like some of the other parts hereinbefore described, may be of any desirable character. It is represented as consisting of a yoke-form detent 26, the bowed branches of which are supported by suitable bearings upon the upper side of the wall 3, the upward motion of the detent 26 being limited by a stop, as 27, connected with said wall and engaging one of said branches. (See Fig. 1.) On one of the branches is a projection, as 28, coöperative with a projection, as 29, on the head 24 of the mandrel. When the machine is not in operation, the projection 28 is in the path of

motion of and adapted to be engaged by the projection 29 in order to prevent the operation of the phonograph 21 by its motor, which, as indicated, I have not deemed it necessary to illustrate. Upon the depression of the detent 26 to carry the projection or shoulder 28 out of contact with the projection 29 the said phonograph will be released and can be operated in such a manner as to secure, as will now appear, one complete rotation of the phonographic cylinder 22. The lower portions of coiled push-springs, as 30, are set into recesses in the upper side of the wall 3 and bear against lugs upon the branches of the detent 26, so as to uphold the latter in its primary position and to return it promptly to said primary position when released. When the detent is depressed, as previously stated, the phonograph will be free to be operated, and the instant the pressure upon the detent is relieved it is promptly returned to its original position by the power of the springs 30, so that the shoulder or projection 28 will be engaged by the projection 29 on the head 24 of the phonograph - mandrel when the latter has made one complete turn. The stop 27 serves to hold the projection 28 out of engagement with the head 24 as the latter rotates with the other parts in order to avoid friction.

The actuating device for securing the operation of the feed-controlling device or detent 26 is represented as consisting of a lever 31, the forward part of which extends through a slot 32 in the front of the case and is equipped with a handle whereby it can be readily manipulated. The said lever 31 is fulcrumed upon a horizontally-disposed shaft, as 33, extending transversely of the device 35 interiorly of the upper compartment of the case thereof and supported by suitable bearings, as 34, therein. The shaft 33, as will be understood, is non-rotative, the lever 31 being freely movable upon the same. Extending 40 through a vertically-disposed tube, as 35, in the upper compartment of the case 2 is a plunger, as 36, the lower portion of which also extends through a perforation in the wall registering with the bore of the tube 35 and formed 45 in the wall 3, to the upper face of which said tube is fixed. The lower end of the plunger 36, which is represented as consisting of a cylindrical rod, engages the tail of the latch 5, the spring 7, which holds said latch in its operative position, also serving to uphold the 50 plunger or rod 36. The upper end of the plunger or rod is adapted for engagement by the rear arm or branch of the lever 31. When the forward branch of said lever is elevated, 55 the rear branch thereof will be lowered in order to impart a downward thrust to the plunger 36 and a corresponding movement to the tail of the latch 5, whereby the working portion of the latch, should a sufficient 60 movement be imparted to the lever, will be 65

disengaged from the rear wall of the drawer 4 to release the latter. The instant that the drawer is released the spring 8 by expanding opens the same. It will be remembered that the forward or handle portion of the lever 31 extends through a slot 32 in the forward side of the casing 2. The lower wall of the slot is illustrated as having a row of notches, each designated by 37, into one of which the lever normally fits, as indicated in Fig. 4. The notches align from the front to the rear of the machine with the respective printing members 18, as indicated in Fig. 3. The lever 31, as has been stated, is fulcrumed upon the stationary shaft 33, from which it will be apparent that the lever in addition to having a swinging or vertical movement is also capable of movement laterally of the apparatus, so that it can be moved sidewise to be brought over the head of any one of the laterally-separated printing members 18. Under the notched portion of the front plate of the case I mount a plate, as 38, bearing on its face numerals corresponding with those of the printing members and which in the present case are five in number and run from "5" to "25." The reproducer for the phonograph is operated by the lever and is denoted in a general way by 39, and is illustrated as carried by the said lever in order to secure the function set forth. Connected with the top of the casing 2 is a horn or trumpet, as 40, which has a connection interiorly of the casing with the reproducer 39 by a flexible tube, as 41. The phonographic cylinder 22 has sound-records thereon laterally separated or spaced from each other and agreeing with the numerals of the indicating mechanism. The construction is such that when a printing member is operated—say the printing member bearing the numeral "5"—the reproducer of the phonograph will be simultaneously put into operative relation with the "5" sound-record of the said cylinder, so as to announce the operation of said printing member. The same operation follows with respect to the remainder of the numeral sound-records on said cylinder.

As previously indicated, the lever 31 will be fitted within one of the notches 37 in the forward side of the casing 2, and it is shown as being in Figs. 3 and 4 in the intermediate notch, or what might be considered the "15" notch. When in such relation, the lever between its fulcrum and handle will rest upon the transverse portion of the yoke-form detent 26, and said lever is upheld in its normal position by the springs 30. It will be assumed that it is desired to make a record of a five-cent sale. Initially the lever will be lifted to carry it out of the intermediate notch, in which it is shown in Fig. 1, and as the lever moves out of the notch its rear end thrusts the plunger 36 downward to effect the operation of the latch 5 and the release by the lat- 130

ter of the drawer or till 4. When the drawer is released, it is at once opened by the power of the spring 8. To record the five-cent sale, the lever 31 is moved toward the left and put 5 into the extreme notch 37 on the left in Figs. 3 and 4, and as it enters said notch it will move against and depress the corresponding printing member 18 sufficiently to cause the action of the printing member against the 10 tape received from the spool or reel 11. As the printing member is operated by the lever the latter simultaneously presses the detent 26 downward, so as to move the shoulder 28 away from the projection 29 and release the 15 phonograph 21, whereby the latter can be operated by its motor. As soon as an impression is made upon the tape by the printing member, and this is an operation that is a rapid one, the lever is released and is re- 20 turned to its original position by the power of the springs of the detent 26 and the printing member which was operated by said lever. By reason of the fact that the detent 26 is illustrated as being of yoke form it may be 25 depressed in the different lateral positions of the said lever by the engagement of the latter with the transverse portion of the detent. When the drawer is closed, the spring 8 is put under compression, and when fully closed is 30 held in such position by the latch 5.

I impart a step-by-step motion to the tape or ribbon of paper unwound from the reel or spool 11, and this result may be accomplished by the operation of the lower feed-roll 12, 35 which, it will be remembered, is carried rigidly upon the shaft 13. Upon said shaft 13 is a gear-wheel 40^a, arranged for step-by-step operation by an actuator, as 41^a, on the forward end of the shaft 42, the rear end of said 40 shaft being connected by bevel-gearing (denoted in a general way by 43) with the phonograph, whereby when the latter is operated in the manner hereinbefore described the shaft 42 will be likewise operated. The parts 45 are so arranged that upon one complete turn of the phonographic cylinder a complete rotation of the shaft, and necessarily of the actuator 41^a rigidly carried thereby, is secured. The actuator consists of a hub having a single 50 tooth, which normally occupies the position shown in Fig. 2. In said figure I have indicated by the arrow the direction of rotation of the actuator, the tooth thereof being out of mesh with the teeth of the gear 40^a. When, 55 however, the actuator has made nearly a complete rotation, its tooth will enter between two teeth of the gear 40^a and will move the latter a distance equaling the space between two teeth, the motion of the gear 40^a being 60 completed when the tooth of the actuator reaches its original position. During the motion of the gear 40^a the lower roll 12 is being moved correspondingly, so as to impart an advancing motion to the paper in a positive

manner. It will be understood that the actuator 41^a does not operate the gear 40^a until after an impression has been made upon the paper or tape unwound from the reel or spool 11.

Having thus described my invention, what I claim is—

1. In an indicator, a phonograph, a feed-controlling device for the phonograph, indicating mechanism, and a lever laterally movable, for operating a desired member of the indicating mechanism and simultaneously the feed-controlling device to release the phonograph, the latter having a reproducer operable by the lever.

2. In an indicator, a phonograph, a feed-controlling device for the phonograph, indicating mechanism, a lever laterally movable, for operating a desired member of the indicating mechanism and simultaneously the feed-controlling device to release the phonograph, the latter having a reproducer operable by the lever, a cash-drawer, a locking device for holding the cash-drawer in a retracted position, and means operable by the said lever, for actuating the locking device to release said cash-drawer.

3. In an indicator, a phonograph, a feed-controlling device for the phonograph, indicating mechanism comprising a plurality of laterally-separated printing members, a laterally-movable lever for simultaneously operating a printing member, and the feed-controlling device for the phonograph, the latter having a reproducer, carried by said lever.

4. In an indicator, a phonograph, a feed-controlling device for the phonograph, indicating mechanism, a laterally-movable lever adapted also for swinging movement, the lever on its lateral movement being adapted to be brought into position to operate different members of the indicating mechanism, and to simultaneously operate the feed-controlling device to release the phonograph, a cash-drawer, a locking device for holding the cash-drawer in a retracted position, and mechanism adapted, on the swinging motion of the lever, to be operated in a direction to actuate the locking device to release the said drawer.

5. In an indicator, a phonograph, a feed-controlling device for the phonograph, a swinging and laterally-movable lever, the lever, on its lateral movement, being adapted to be brought into position to operate different members of the indicating mechanism, and simultaneously to operate the feed-controlling device to cause the operation of the phonograph, a cash-drawer, a locking device for retaining the cash-drawer in a retracted position, and a plunger arranged for endwise movement by the lever on the swinging movement of the latter and serving, on such

endwise movement, to operate the locking device in a direction to cause the release of said drawer.

6. In an indicator, a phonograph, a feed-controlling device for the phonograph, a plurality of printing members, a table, means for supporting a strip of paper for movement across said table, a laterally movable and swinging lever adapted, on its lateral movement, to be brought into position to operate the respective printing members to cause their action against said paper, and to simultaneously operate the feed-controlling device in a direction to cause the action of the phonograph, a cash-drawer, a locking device for the cash-drawer, and mechanism arranged for operation by the lever on its swinging movement, to actuate the locking device in a direction to effect the release of said drawer.

7. In an indicator, a phonograph, a feed-controlling device for the phonograph, indicating mechanism involving printing members, a lever provided with a reproducer for the phonograph, arranged to simultaneously operate the indicating mechanism, and the feed-controlling device, means for supporting a strip of paper to receive the impressions, and mechanism to positively feed the paper.

8. In an indicator, a phonograph, a feed-controlling device for the phonograph, indicating mechanism involving printing members, a lever provided with a reproducer for the phonograph, arranged to simultaneously operate the indicating mechanism and the feed-controlling device, means for supporting a strip of paper to receive the impressions, and mechanism operative with the phonograph for positively feeding the paper.

9. In an indicator, a phonograph, a yoke-form feed-controlling device for the phonograph, indicating mechanism, and a lever, laterally movable, to engage different members of the printing mechanism, and provided with a reproducer for the phonograph, said lever, in its different lateral positions, being adapted to operate the feed-controlling device in a direction to cause the action of the phonograph.

10. In a machine of the class described, a phonograph, a feed-controlling device for the phonograph, indicating mechanism involving printing members, a laterally-movable lever having a reproducer for the phono-

graph, and arranged, on its lateral motion, to be brought into position to operate different printing members of the indicating mechanism and simultaneously to operate said feed-controlling device, means for supporting a strip of paper in position to receive the impressions of the printing members, a pair of feed-rolls between which the paper is led, a gear connected with one of said feed-rolls, and a single-toothed actuator, operative with the phonograph, and its tooth serving to operate said gear.

11. In an indicator, a phonograph, a yoke-form spring-controlled feed-controlling device for the phonograph, a laterally-movable member for operating the indicating mechanism and simultaneously operating the said feed-controlling device, the latter, when operated, serving to permit the action of the phonograph, the reproducer of said phonograph being carried by said laterally-movable member, a horn, a flexible tube between the reproducer and horn, a cash-drawer, a locking device for holding the cash-drawer in a retracted position, and mechanism operable by said laterally-movable lever, the latter being capable of swinging movement to secure such action, to effect the operation of the locking device and the release of said cash-drawer.

12. An indicator having a phonograph, a feed-controlling device for the phonograph, indicating mechanism, a laterally movable and swinging member adapted on its lateral movement to be brought in position to operate different members of the indicating mechanism, a notched portion, into one of the notches of which the laterally movable and swinging member is adapted normally to fit, the latter having a reproducer for the phonograph, a cash-drawer, a locking device for holding the cash-drawer in a retracted position, and mechanism operable on the swinging motion of said laterally movable and swinging member for operating the said locking device in a direction to effect the release of said cash-drawer.

In testimony whereof I have hereunto set my hand in presence of two subscribing witnesses.

CORNELIUS S. CLARK.
